Patented Aug. 9, 1927.

UNITED STATES PATENT OFFICE.

STEPHEN STANCIU, OF ST. PAUL, MINNESOTA.

ARMLET FOR INFANTS.

Application filed March 13, 1926. Serial No. 94,453.

My invention relates to armlets for infants and has for its object to provide a device which may be readily attached to the arm of an infant at the elbow for the purpose of preventing the infant from bending its arms sufficiently to bring its hand to its face.

Another object is to provide a body member of semi-pliable leather or other suitable material adapted to be bent longitudinally around the arm of the infant but having sufficient stiffness to prevent transverse bending thereof and in forming said body member so that the longitudinal marginal portions thereof lie spaced from one another and extend outwardly from the arm so as to permit of free circulation of the blood.

A still further object of the invention resides in providing a lacing for securing the armlet upon the arm, which lacing is threaded across said marginal portions so as to leave an opening medially between the ends of the armlet through which the elbow may protrude for the purpose of preventing the sliding of the armlet along the arm.

A feature of the invention resides in reducing the thickness of said body member along the end marginal portions of the armlet and of bending said portions outwardly to provide rolled edges where the armlet terminates for the prevention of injury by abrasion to the infant's arm.

With the foregoing and other objects in view, which will appear in the following description, the invention resides in the novel combination and arrangement of parts and in the details of construction herein-after described and claimed.

Changes in the specific form of my invention, as herein disclosed, may be made within the scope of what is claimed without departing from the spirit of my invention.

In the drawings illustrating my invention:

45 Fig. 1 is a perspective view of an embodiment of my invention.

Fig. 2 is a longitudinal sectional view of the structure illustrated in Fig. 1 showing the same as applied to an arm illustrated in 50 dotted lines as being partly bent.

Fig. 3 is a cross sectional view of the device.

Fig. 4 is a plan view of a blank of the stock from which the armlet is formed.

55 Fig. 5 is a fragmentary sectional view of

a marginal portion of the armlet drawn to an enlarged scale.

Many infants form the undesirable habit of sucking their thumbs of which it becomes exceedingly difficult to break them. My improved armlet provides a means whereby the infant is prevented from the bending of the arm sufficiently to carry its thumb to its mouth. Furthermore, infants are frequently inflicted with skin diseases causing eruptions upon the face which itch and tempt the infant to scratch, which practice causes infections and retards the recovery of the infant from the disease. My armlet is also useful in such instances in that it prevents 70 the infant from bringing its hands into contact with its face.

The armlet is indicated in its entirety at A and consists of a body member 10 cut from a sheet of leather in the shape of a trapezoid as indicated in Fig. 4, having two parallel edges 11 and 12 and two converging edges 13 and 14, the corners of the same designated at 30, being rounded off. The stock from which the body member 10 is cut is 80 preferably of sufficient degree of stiffness to prevent the bending of the armlet transversely and yet of sufficient pliability to permit the same to be bent longitudinally in substantially cylindrical formation, as will 85 be presently described.

Along the marginal portions 16 of the body member 10 adjacent the converging edge 13, I punch a number of holes 18, 19, 20, 21, 22 and 23, which are arranged in a line lying substantially parallel to said edge 13 and inwardly therefrom. The holes 18, 19 and 20 are rather closely spaced being substantially the same distance apart and likewise the holes 21, 22 and 23. The holes 90 20 and 21 are, however, more remotely spaced than the distance between any of the other holes for a purpose soon to be explained. Along the marginal portion 17 of body member 10 adjacent the edge 14 are 100 provided holes 24, 25, 26, 27, 28 and 29, which are situated with respect to the edge 14 and to one another the same as the holes 18, 19, 20, 21, 22 and 23, just mentioned.

In using my improved armlet the body member 10 is bent to take the form illustrated in Fig. 1 and a lacing 31 threaded through the various holes along the marginal portions 16 and 17 thereof to cause said lacing to extend across the edges 13 110

and 14 of said body member. The armlet upon being loosely laced may be slipped over the arm of the infant and is positioned with the elbow of the infant between the 5 portions of the lace indicated at 32 and 33. Lacing 31 is then tightened to bring the armlet to fit around the infant's arm as shown in Fig. 3 and the end 34 secured in place. It will be noted that when so arranged the edges 13 and 14 do not engage the arm but extend outwardly therefrom in such a manner as to hold the lacing 31 away from the arm proper. This allows the 10 blood to circulate freely through the arm so as to offer no discomfort to the wearer. When the bending of the elbow is initiated, the lacing 31 is brought in contact with the infant's arm and particularly the portions 32 and 33 thereof which catch below and 15 above the elbow and prevent the armlet from being displaced. The infant does not become fatigued in the use of the device due to the holding of its elbow in a substantially fixed position as the armlet, when 20 laced as indicated in Fig. 3, permits of bending the elbow sufficiently to relax the muscles, without allowing the hand to reach the 25 face.

To prevent the chafing or irritation to the 30 infant's arm from the end edges 10 and 11 of the armlet A, the marginal portions 35 and 36 of body member 10 adjacent the edges 10 and 11 are formed as shown in detail in Fig. 5. This is accomplished by cutting away the inner surface of the marginal portions 35 and 36 so as to gradually reduce the thickness of the body member 10 towards the edges 11 and 12 thereof and by turning the same over and stretching said 35 marginal portions along their thinnest portions so as to produce in effect a rolled edge along the end portions of the armlet. These edges will in no manner irritate the infant's arm, whether the armlet is applied 40 over the infant's clothing or directly upon the arm.

For the purpose of ventilation, the body member 10 is provided with rows of perforations 37 and 38 along the marginal portions 50 16 and 17 thereof and rows of perforations 39 and 40 along the marginal portions 35 and 36. These perforations prevent the armlet from becoming uncomfortable to the wearer through perspiration being, however, so situated as to leave a smooth surface 55 along the central portion of the armlet where the same might be brought in contact

with the infant's face in its endeavors to bring its hands in proximity thereto.

My improved armlet is exceedingly simple 60 in construction and may be easily applied and attached to the arm of an infant. When properly applied it prevents the infant from bringing its hands to its face without giving it the least discomfort or annoyance. 65

Changes in the specific form of my intention, as herein disclosed, may be made within the scope of what is claimed without departing from the spirit of my invention.

Having described my invention, what I 70 claim as new and desire to protect by Letters Patent is:

1. An armlet for infants comprising an elongated body member of semi-pliable material adapted to be bent longitudinally 75 thereof around the arm and elbow, said member being of sufficient stiffness to prevent the bending thereof transversely, the longitudinal marginal portions thereof terminating in spaced relation to one another, 80 and a lacing between said marginal portions, adjacent reaches of said lacing being spaced sufficiently medially of said body member to provide a space for the protrusion of the elbow, said adjacent reaches of 85 said lacing serving to engage the arm above and below the elbow to hold the armlet from sliding along the arm.

2. An armlet for infants comprising an elongated body member or semi-pliable material adapted to be bent longitudinally 90 thereof around the arm and elbow, said member being of sufficient stiffness to prevent bending in a transverse direction, the longitudinal edges of said member falling 95 short of one another and protruding outwardly from the arm to leave a free space therebetween into which the elbow may extend, and means for holding the edges of 100 said member in proper relation.

3. An armlet for infants comprising an elongated body member of semi-pliable leather adapted to be bent longitudinally 105 thereof around the arm and elbow, said member being of sufficient stiffness to prevent bending in a transverse direction, the end marginal portions of said body member being reduced in thickness and turned outwardly to form pliable protective edges, and means for attaching said member in 110 place upon the arm.

In testimony whereof, I have signed my name to this specification.

STEPHEN STANCIU.
